UNITED STATES PATENT OFFICE.

CHARLES A. BRINLEY, OF PHILADELPHIA, PENNSYLVANIA.

SHAFT-HANGER.

SPECIFICATION forming part of Letters Patent No. 699,943, dated May 13, 1902.

Application filed March 23, 1901. Serial No. 52,526. (No model.)

To all whom it may concern:

Be it known that I, CHARLES A. BRINLEY, of the city and county of Philadelphia and State of Pennsylvania, have invented an Improvement in Shaft-Hangers, of which the following is a specification.

My invention has reference to shaft-hangers; and it consists of certain improvements all of which are fully set forth in the following specification and shown in the accompanying drawings, which form a part thereof.

The object of my invention is to provide a suitable construction of drop-hanger for shafting, which, while retaining the general characteristic shape of such hangers found by experience as best adapted for the purpose, shall embody special improvements whereby commercial sections of rolled iron or steel may be employed in its construction. The result of such construction is to produce a hanger of composite form and of great rigidity coupled with lightness, the latter features being secured by properly shaping and bracing the light rolled-metal bars used in the construction.

My object is further to so construct the hanger that the lower or box-supporting portion may be detachable and employed in combination with hanger-bases having the arms of various lengths to secure different "drops," thereby simplifying the manufacture to suit all possible demands, and to provide means whereby the lower parts carrying the box can be made up without reference to the drop and any one of the lower parts can be employed with any upper part of several such upper parts, thus simplifying the manufacture.

In carrying out my invention I form the base and depending arms of the hanger of lighter rolled iron or steel, preferably of L shape in cross-section, and I so shape and combine the several parts that the proper configuration is secured with a simple bracing, which permits lightness to be had without impairing the great stability and rigidity so necessary to shaft-hangers in commercial use. The lower ends of the depending arms or body portion of the hanger-frame are united by suitable bracing, adapted also to carry the screws which support the journal-box. In place of making the lower portion of the

hanger-frame arms or members integral with the upper or base portion it may be made separate and riveted, bolted, or otherwise secured to the upper portion, as will be more fully explained hereinafter. The lower portion of the hanger may have the lower cross-braces riveted or otherwise secured to the upright members; but I prefer to have the lower transverse brace detachably secured in place, so that the shaft and journal-box may be put into place within the hanger from below and the brace and support for the box then secured in place by preferably detachable means, such as bolts.

My invention will be better understood by reference to the drawings, in which—

Figure 1 is a front elevation of a shaft-hanger embodying my invention. Fig. 2 is an inverted plan view of same. Fig. 3 is a side elevation of same. Fig. 4 is a front elevation of a modification of same, showing the detachable lower portion carrying the journal-box; and Fig. 5 is a plan view of the hanger shown in Fig. 4.

A represents four depending arms of angle-iron, their upper ends being bent outward, as at A', and their lower ends bent vertically, as at D. The middle portions of these arms A are oblique and also, preferably, spreading at their upper ends to give greater base of support. To make a sharp bend between parts A and A', one rib of the angle-iron is notched out and the edges butted and the joint strengthened by corner-braces B'. The outer ends of the footpieces A' are connected in pairs by the cross-plates C, riveted to them, said plates having the necessary holes c for attaching the hanger to the ceiling-timbers. These plates C are preferably of angle-iron, transversely arranged, and in addition to these the angle-iron arms A may be connected in pairs in the other direction at the top by bars B of any suitable cross-section, which are properly riveted in place, as shown. In this manner the parts A', C, and B make a strong and extensive base of support, and thereby prevent any tendency to rocking due to strains upon the shafting.

The lower ends D of the arms A are preferably vertical, and hence parallel. They are connected in pairs by the braces H H, the two pairs of arms thus formed being also connect-

- ed by braces E F. These braces E F are arranged at different elevations, so as to leave a space between them sufficient for the journal-box J, through which the shaft G passes.
- 5 The other braces H H are at a middle elevation or between the levels of the two braces E F. As will be seen from Fig. 2, the brace E is composed of two U-shaped pieces riveted together to form an H-shaped structure, the 10 ends of the arms being bolted to the flanges of the parts D of the lower body portion. The brace E is detachably secured to the said parts D by bolts K, whereby it may be removed for inserting the line of shafting and then secured 15 in place to support it. The adjusting and supporting screw e passes through the bar formed in this brace. The upper brace F is made in exactly the same way and is provided with a similar screw f for holding the box.
- 20 The screw f presses down upon the cap of the box, and the screw e presses upward under the body of the box, so that their joint action holds the two parts of the journal-box together, as well as adjusts its position in the hanger. The 25 side braces H H are made like I-shaped structures formed of two pieces riveted together and with the flanges riveted to the flanges of parts D, as shown in Fig. 3. Screws h pass through these braces H and act as adjusting 30 and steadyng devices for each side of the journal-box G. The braces F and H may be riveted to the parts D, as shown, or permanently attached in any suitable manner. The braces H, E, and F thoroughly connect and 35 brace the ends D of the arms A, so as to impart great rigidity, and form excellent supports for the screws, which directly sustain the journal-box.
- The foregoing description more specifically 40 relates to Figs. 1, 2, and 3, in which the parts A and D are in one integral structure. I will now refer to Figs. 4 and 5, which show a modified form of base and a sectional construction 45 for the hanger-frame. In these figures the arms A are made flaring, as before, but are riveted direct to the flanges of an angle-iron base B². In this case the angle-irons B² B² are curved, as shown, and riveted together at the middle at b and constitute an X structure, 50 the free arms of which are riveted to the upper ends of the arms A. The cross-plates C are used also in this case as in the other and may be of flat metal or rolled shapes, as preferred.
- 55 The lower ends of the arms A are preferably made similar to those of Fig. 1, but shorter and without bracing. The journal-box-supporting devices, precisely like those described, (except that the parts D are independent of 60 the arms A, as shown in Fig. 4,) are then placed in position, so that the arms A overlap the parts D', and are riveted or bolted together at d. In this manner the lower body portion or journal-box-supporting structures 65 may be made up in quantities and the upper portions of the hanger made to suit the special

requirements as to drop or construction of base.

The lower body portion when made separate is the same for a number of different upper body portions or bases, and if these parts are kept in stock hangers of any desired drop or shape of base may be made by mere assembling of the upper and lower body portions by uniting the upright members of the two parts. Of course in cases where a large order is desired of a hanger of one drop the upright members may be made continuous or integral, as in Fig. 1.

A hanger of this construction is cheap to 80 make, is lighter, and consequently cheaper to transport, and is stronger than cast-iron hangers commonly employed.

While I have shown my improved hanger as made largely from angle-iron, I do not confine myself to any special cross-section of rolled metal, and while I prefer the construction shown as being an excellent embodiment of my invention I do not confine myself to the minor details, as these may be modified 90 without departing from the spirit of the invention.

Having now described my invention, what I claim as new, and desire to secure by Letters Patent, is—

1. A shaft-hanger having a lower body portion consisting of a light open frame comprising four corner-uprights connected by cross-braces two of said braces connecting all four uprights so as to leave an open space transversely through the said body portion and the other two braces connecting the uprights in pairs and leaving a vertical space between the uprights and first-mentioned two braces, in combination with a journal-box arranged 105 in the open space between all the braces, and vertical and horizontal screws carried by said cross-braces for holding the journal-box in position.

2. In a shaft-hanger the combination of 110 four depending arms A of angle-iron substantially equidistant at the bottom and spreading at the top to form a large supporting-base, transverse plates C riveted to the upper ends of the said arms to properly space them in 115 pairs, braces H connecting the lower portions or extensions of the arms in pairs, upper and lower braces F and E for connecting the two pairs of arms A at points above and below the braces H, a removable journal-box J arranged between the braces H, F and E, and adjusting and supporting screws h, f and e for said box carried respectively by said braces.

3. In a shaft-hanger the combination of 125 four depending arms A of angle-iron substantially equidistant at the bottom and spreading at the top to form a large supporting-base and in which the lower portions of the arms are made detachable from the upper portions, 130 transverse plates C riveted to the upper ends of the said arms to properly space them in

pairs, braces H connecting the lower portions or extensions of the arms in pairs below the union of the upper and lower portions of the arms A, upper and lower braces F and E for connecting the lower portions of the two pairs of arms A at points above and below the braces H but also arranged below the union of the upper and lower portions of the said arms A, a removable journal-box J arranged between the braces H, F and E, and adjusting and supporting screws *h f* and *e* for said box carried respectively by said braces.

4. A shaft-hanger having a lower body portion consisting of four upright angle-irons, combined with braces for connecting said uprights in two pairs, two other braces for connecting the two pairs of uprights into a single structure said last-specified braces being arranged respectively above and below the level of the first-mentioned braces, and a journal-box supported between the four braces and four uprights.

5. A drop-hanger consisting of a body portion comprising four upright flanged metal members flaring or spreading at the top, combined with transverse plates connecting the tops of the members to form an extended base, braces H rigidly connecting the said members in pairs, braces F and E connecting the pairs of members together and located re-

spectively at a higher and lower elevation than the braces H, a journal-box J arranged between the braces, and screws passing through the braces and supporting the journal-box.

6. A shaft-hanger frame formed of flanged metal bars and having its body portion formed of four upright members united at the top by transverse plates C C and the two curved angle-iron bars B² B² secured together at their middle portions and having their ends secured to the upright members.

7. In a drop-hanger the combination of four upright members, transverse side braces connecting said upright members in two pairs, a transverse brace connecting the two pairs of upright members at a level above the side braces, and a second transverse brace between the two pairs of upright members and at a level below the side braces, detachable means for connecting the last-mentioned and lowermost brace to the upright members, supporting and adjusting screws carried by the braces, and a journal-box supported by said screws.

In testimony of which invention I have hereunto set my hand.

CHARLES A. BRINLEY.
